UNITED STATES PATENT OFFICE.

GEORGE H. PERRINE, OF GREENBURG, NEW YORK.

NECKTIE-GUIDE FOR FOLDED COLLARS.

1,173,735.

Specification of Letters Patent. Patented Feb. 29, 1916.

Application filed July 2, 1915. Serial No. 37,726.

To all whom it may concern:

Be it known that I, GEORGE H. PERRINE, a citizen of the United States, residing at Greenburg, in the county of Westchester and State of New York, have invented a 5 certain new and useful Improvement in Necktie-Guides for Folded Collars, of which the following is a full, clear, and exact description.

10 The object of this invention is to provide a simple, cheap and efficient means by which the necktie may have free play between the folds of folded or turned-down collars, so as to be capable of ready slipping without binding in the act of adjusting the ends to 15 suit the wearer in tying the necktie, and to prevent the necktie from working up between the folds of the collar.

15 The invention consists of a strip of any 20 suitable material, such as cardboard, fiberboard, rubber, celluloid, metal, or the like, that will receive and retain embossed or otherwise applied projections, and that may be inserted between the folds of the collar, 25 space apart said folds, and afford through 30 its projections a stopping means to limit the location of the necktie and prevent it from binding or sticking and so refusing to slip lengthwise between the folds of the collar, as I will proceed now to explain and finally claim.

35 In the accompanying drawings illustrating the invention, in the several figures of which like parts are similarly designated, 40 Figure 1 is a perspective view showing a folded or turned-down collar, partly broken away at the back of the band, with one form of guide in position, and also showing in dotted lines, a portion of a four-in-hand necktie in position. Fig. 2 is an elevation, 45 and Fig. 3 is a cross-section of the form of guide shown in Fig. 1 detached, taken on line A B, of Fig. 2. Fig. 4 is a perspective view of another form of guide. Fig. 5 is a perspective view of still another 50 form of guide. Fig. 6 is an elevation of a portion of one form of guide having attached projections, and Fig. 7 is a cross-section of the same on line C D, Fig. 6.

55 The guide 1 may be a short strip of suitable material, adapted to be applied between the folds of a turned-down or folded collar at the back and extending toward the front on both sides, as shown in Figs. 1 and 2; or it may be a longer strip, as shown in Figs. 4, 5 and 6, that will extend well for-

ward to the front of the collar on both sides; and in either case the bottom edge of the guide may be cut away as at 2, so as not to interfere with the use of the button-hole 3 at the back of the collar 4. This guide may be made of any suitable material, such as cardboard, fiberboard, rubber, gutta percha, celluloid, metal, or the like, and preferably inherently waterproof, or rendered waterproof, and sufficiently rigid to hold its shape and to retain in shape the projections thereon when made integral therewith, or to hold such projections in place when affixed to it. As shown in Figs. 1 and 2, these projections, 5, are embossed or struck up in the material so as to stand off therefrom, as shown in Fig. 3, and present shoulders 6 against which the upper edge of the necktie abuts and runs in adjusting the necktie in the 75 collar when applied to a wearer's neck, thus preventing the necktie from unduly riding up into the upper portion of the collar between its folds. These projections likewise serve to space apart or separate the folds 80 of the collar sufficiently to permit the necktie to be slipped easily in the collar in order to effect the adjustments desired by the wearer in tying the necktie. As shown in Figs. 1, 2 and 3, these projections may be 85 of triangular shape, running out to nothing at the top; or as shown in Fig. 4 the projections 7 may be of triangular shape, standing off from the strip, more or less, throughout 90 their entire extent; or as shown in Fig. 5 these projections 8 may be oval and of substantially uniform cross-section; or as shown 95 in Figs. 6 and 7 the projections 9 may be substantially like shoe lacing-hooks or studs provided with eyelets by which they may be riveted to the strip. But the invention is not limited to the form or construction of projections, excepting as hereinafter claimed.

100 It is advisable to locate the projections below the upper edge of the strip and above its lower edge and at or about the longitudinal center of the strip, so that the strip may be placed between the folds of the collar and extend up to its upper edge without unduly 105 separating the folds at the upper portion of the collar and yet space apart or separate them in a plane between its upper and lower edges to such an extent that the necktie may be placed in between the folds of the 110 collar next to the inner fold or band and with its outer side against the body of the

strip and its upper edge alining with the shoulders or lower edges of the projections or portions, and in this way the tendency of the folds of the collar to close down tight 5 one upon the other when applied to a shirt will be overcome and sufficient space will be afforded between them to permit the free slipping of the necktie when the wearer adjusts it for tying purposes. In this way the 10 strain of tugging on the necktie in order to cause it to slip between the folds of the collar is obviated, and the tie is prevented from becoming stringy as so often happens when the material of the necktie is such as 15 to cause excessive friction between itself and the folds of the collar when the necktie is moved lengthwise.

What I claim is:—

1. A necktie guide, for folded or turned-down collars, comprising a strip of suitable material adapted to be inserted between the folds of the collar and of a length sufficient to extend from the back forward along both sides of the collar, and provided with projections located between its upper and lower edges and presenting shoulders at their lower portions against which the upper edge of the necktie abuts, and by which the upward movement of the necktie between the 25 folds of the collar is arrested, said shoulders serving also to space apart or separate the folds of the collar sufficiently to permit the necktie to be freely slipped lengthwise between the folds of the collar.
2. A necktie guide for folded collars, comprising a strip of rigid material of a length sufficient to extend from the back of the collar forward along both sides of the collar, and having embossed projections therein located between the upper and lower edges of 30 35 40

the strip and serving to arrest the upward movement of the necktie and to space apart or separate the folds of the collar and thereby permit free lengthwise movement of the necktie between said folds. 45

3. A necktie guide for folded collars, comprising a strip of rigid material of a length sufficient to extend from the back of the collar forward along both sides of the collar and having embossed projections therein located between the upper and lower edges of the strip and having well defined shoulders at their lower portions which serve to arrest the upward movement of the necktie and to space apart or separate the 50 55 folds of the collar and thereby permit freedom of movement of the necktie in the direction of its length when placed between said folds and below said projections.

4. A necktie guide for folded collars, comprising an elongated strip of rigid material adapted to extend from the back of the collar forwardly toward its front and having embossed projections therein extending out from one side thereof and located between the upper and lower edges of the strip and having well defined shoulders at their lower portions and disappearing in the body of the strip above, and serving to arrest the upward movement of the necktie and to space apart or separate the folds of the collar to thereby permit the necktie to be freely slipped lengthwise between the said folds in order to adjust it for tying. 60 65 70

In testimony whereof I have hereunto set my hand this first day of July A. D. 1915.

GEORGE H. PERRINE.
